DESIGN FOR A VACUUM CLEANER CASING

Edgar P. Senné, Rockville Centre, N. Y.

Application October 9, 1946, Serial No. 133,855

Term of patent 14 years

(Cl. D9—2)

To all whom it may concern:

Be it known that I, Edgar P. Senné, a citizen of the United States of America, residing in Rockville Centre, in the county of Nassau and State of New York, have invented a new, original, and ornamental Design for a Vacuum Cleaner Casing, of which the following is a specification, reference being had to the accompanying drawings, forming part thereof.

In the drawings:

Figure 1 is a perspective view, as seen from a point above and to one side thereof, of a vacuum cleaner casing, showing my new design.

Figure 2 is a front elevation thereof.

Figure 3 is a rear elevation thereof.

I claim:

The ornamental design for a vacuum cleaner casing, substantially as shown.

EDGAR P. SENNÉ.
